(57) **CLAIM**

The ornamental design for a license plate holder, as shown and described.

DESCRIPTION

FIG. 1 is a front view of a license plate holder showing the design;

FIG. 2 is a left side elevational with the right side being a mirror image thereof;

FIG. 3 is a top plan view with the bottom plan view being a mirror image thereof; and,

FIG. 4 is a new elevational view.

The license plate shown in dashed lines is not part of the design.
